UNITED STATES PATENT OFFICE

2,512,074

PACKAGING MACHINE FOR CANDY,
COOKIES, AND THE LIKEOscar Sandberg, Toledo, Ohio, assignor to Lynch
Package Machinery Corporation, Toledo, Ohio,
a corporation of Ohio

Application September 18, 1946, Serial No. 697,782

1 Claim. (Cl. 93—1)

1 This invention relates to packaging machines for candy, cakes and the like, and particularly to the forming, cutting, and feeding of cards and "boats" usually placed underneath the article to be wrapped, primarily to facilitate wrapping with cellophane, wax paper or the like.

Ordinarily, flat, rectangular cardboard or heavy paper cards are used when candy bars, cakes or the like in one piece are wrapped in a single package, while so-called "boats," which are merely heavy paper or cardboard strips bent to generally U-shaped form, are used when the candy or cakes to be wrapped in a single package are in several pieces and the single package is to be substantially rectangular in shape. Except for the shape of the cards and boats, however, the wrapping machine for wrapping either type of articles is substantially, and, in most cases, exactly the same and it is desirable, therefore, that the machine be easily changed for wrapping with either cards or boats, particularly in view of the fact that such wrapping machines are rather costly, and manufacturers do not wish to buy two or more machines for wrapping the aforesaid two types of merchandise.

Furthermore, I have found that the cards and boats may be fed from a reel or spool of material and cut off with greater facility than feeding them from a stack, and while the present invention is not limited to such feeding, it is particularly adaptable thereto. The method of wrapping including feeding cards or boats from a reel is fully disclosed and claimed in my copending application, Serial No. 722,149 for Method of wrapping articles filed January 15, 1947.

It is an object of this invention, therefore, to provide improved mechanism for feeding cards to a packaging machine for candy, cakes and the like.

It is also an object of the invention to provide improved mechanism for feeding boats to a packaging machine for candy, cakes and the like.

It is a further object of the invention to provide mechanism for feeding cards and boats to a packaging machine, part of which mechanism is readily interchangeable for feeding either cards or boats depending on the article to be wrapped and the desire of the operator.

It is another object of the invention to provide improved operating or driving means for a card or boat feeder of the type described.

It is also an object of the invention to provide novel and simple forming means for packaging machine boats.

It is a further object of the invention to provide improved means for cutting off boats and

2 cards for packaging machine use and to insure proper feeding thereof to the pockets in the packaging machine in which the articles to be wrapped are deposited.

5 It is also an object of the invention to provide improved and effective timed feeding and cutting mechanism for such cards and boats, which is synchronized with the conveyor for receiving and moving articles to be wrapped.

10 It is an additional object of the invention to provide feed rolls which are adaptable for feeding either cards or boats and which partially form the boats in a novel manner.

15 It is a further object of the invention to provide unique feeding means for strip material for forming cards or boats and particularly to provide for maintaining the strip material in tension between spaced sets of feed rolls at all times, thus insuring forming of cards and boats of proper length.

20 It is still another object of the invention to provide for adjustment of feed roll pressure and also to provide for adjustment of the boat folding mechanism and card mechanism for different size packages.

25 With these and other objects in view, my invention consists in the construction, arrangement and combination of the various parts of my device whereby the objects contemplated are attained, as hereinafter more fully set forth, pointed out in my claim and illustrated in the accompanying drawing, wherein:

30 Figure 1 is a side elevational view of one side of the card and boat forming and feeding mechanism, with parts thereof in section and with the boat former attached;

35 Figure 2 is a diagrammatic view of the driving mechanism for the card and boat forming and feeding mechanism;

40 Figure 3 is a detail view of the timing gears utilized in the machine;

45 Figure 4 is an end view of a strip of cardboard before it is formed into a boat;

50 Figure 5 is a partial sectional view taken on line V—V of Figure 1 of the first feed rolls with a cardboard strip for forming a boat passing therethrough;

55 Figure 6 is a side elevational view of the other side of the card and boat forming and feeding mechanism shown in Figure 1, with parts shown in section for clarity and with the boat former attached;

60 Figure 7 is a sectional view of the curved boat forming guides taken on line VII—VII of Figure 6;

65 Figure 8 is a sectional view of the discharge

rolls with a strip therein folded to form a boat and is taken on line VIII—VIII of Figure 6;

Figure 9 is a perspective view of a finished boat;

Figure 10 is a front view of the mechanism shown in Figures 1 and 6, the full lines illustrating the cutting knife in the raised position and the dotted lines illustrating the cutting knife in the lowered position;

Figure 11 is a partial view of the machine similar to Figure 1, with the knife in its lowermost position after cutting a boat off the strip of cardboard;

Figure 12 is a partial sectional view taken on line XII—XII of Figure 10;

Figures 13 and 14 are detail top and side views of one boat former guide;

Figure 15 is a top plan view of the feed mechanism and boat and card cutter;

Figure 16 is a partial top plan view of the discharge rolls and card guide attached to the mechanism in place of the boat former, the remainder of the mechanism being identical with that shown in the preceding figures;

Figure 17 is a partial sectional view taken on line XVII—XVII of Figure 16;

Figure 18 is a view of the card forming attachment taken on line XVIII—XVIII of Figure 17; and

Figure 19 is a diagrammatic perspective view of the gears, rollers, et cetera, for operating the card and boat forming and feed mechanism.

Referring specifically to the drawing for a detailed description of the invention, it is first to be noted that the mechanism disclosed is adapted to be associated with any wrapping machine having travelling pockets or the like, in which articles to be wrapped are deposited, and the mechanism may be utilized with the general type of machine shown in my copending application, Serial No. 654,079, filed March 13, 1946 (now abandoned), for Wrapping machine for sandwiches and the like. In that machine, a main drive shaft 95 is driven through a chain 96 and suitable sprockets by a shaft 36, and similar numbers have been used herein, as shown in Figure 2, so that the manner of association and timing of the functions of the present invention with the machine of the aforesaid copending application will be readily apparent. A motor 21 drives a pinion gear 22 through a belt 23, which pinion in turn drives a gear 24 on which is mounted a sprocket 25 for driving a sprocket 26 mounted on shaft 95 through a chain 96. A second sprocket 27 is secured to shaft 95 and drives a chain 28 which rotates a sprocket 29 and a main drive shaft 31 having a main drive gear 32 secured thereto, which main drive gear drives the entire card and boat forming and feeding mechanism in a manner hereinafter described.

Referring particularly to Figures 1, 6, 10, 11 and 15, it will be seen that the entire forming and feeding mechanism is mounted on structural bracket members, generally indicated at 33, which are in turn mounted on bars 34 and 34a. The bars 34 and 34a are supported by spaced upright frame members (not shown) which support the wrapping machine.

Mounted on one end of the structural members 33 adjacent bar 34 are a plurality of pockets 35 moved in steps by a chain conveyor 36a, which is also driven from shaft 95 in a manner shown in the aforementioned copending application. The mounting and drive of the pockets and the chain conveyor forms no part of the present in-

vention, and further description thereof is, therefore, deemed unnecessary.

The structural members 33 are curved upwardly at the right-hand end, as shown at 37 in Figures 5 and 15, and provide bearings 38 and 39 for upper and lower feed roll shafts 41 and 42 which rotate feed rolls 43 and 44, respectively. This end of supporting members 33 also have bearing supports 45 preferably screwed therein for a shaft 10 46 which has a strip guide roll 47 thereon for guiding a strip of cardboard 48 from a freely rotatable reel 49, shown in Figure 2. The guide roll 47 is sufficiently wide to guide strips of cardboard, whether boats or cards are to be formed.

15 The structural members 33 likewise provide support through uprights 52, for a base plate 51, over which the strip 48 travels and on which boat forming guides, generally indicated at 53 and 54, or a card strip guide, generally indicated at 55, are mounted in a manner hereinafter described. Furthermore, the structural members 33 provide a support for a downwardly extending strap 56, which provides a bearing 57 for a shaft 58, to which a single intermediate gear 59 is secured. A gear 60 is mounted on shaft 42 which meshes with gear 59 (see Figure 19) to drive the feed rolls 43 and 44, the gear 60 driving a gear 61 secured to feed roll shaft 41.

One of the structural members 33, as best shown in Figure 1, provides a bearing 62 for shaft 31 of main driving gear 32 and sprocket 29. A cam 63 is also secured to and rotates with shaft 31 for operating a cutting knife 95a, in a manner hereinafter described.

35 Also mounted on structural members 33 adjacent supporting bar 34a are a pair of spaced bearing blocks, generally indicated at 64, providing bearings 65 and 66 for discharge feed roll shafts 67 and 68 which rotate upper and lower feed rolls 69 and 70, respectively. The bearing blocks are adjustable longitudinally of the strip 48 by reason of slots 60a and bolts 60b, which secure the blocks to the brackets 33, thus enabling the device to form cards or boats of somewhat different lengths. The lower feed roll shaft 68 has a sprocket 71 secured thereto, which is driven by a chain 72 which is in turn driven by a sprocket 73 rotated by feed roll shaft 42. The upper discharge feed roll shaft 67 has a gear 74 thereon which meshes with a gear 75 on the lower discharge feed roll shaft 68 and drives the same.

The structural members 33 also provide spaced bearings 76 for a shaft 77 which has a gear 78 thereon driven by main gear 32, and a gear 79 thereon which drives idler gear 59 and thereby drives the two sets of feed rolls 43, 44 and 69, 70. It is to be noted that main drive gear 32 and driven gear 78 are provided with cooperating flat portions 81 and 82, respectively, as well as 55 60 when the feed rolls are not driven.

Referring now to the first feed rolls 43 and 44, it will be noted that the lower feed roll 44 is larger than the upper feed roll 43 and is provided with spaced circumferential grooves 83. The upper feed roll 43 is provided with circumferential ridges 84 which are received in the grooves 83 of feed roll 44, as best shown in Figure 5. When cards are to be cut, the strip of cardboard 48 fits between the grooves and ridges 83 and 84, and is merely guided by them. When boats are to be formed, as shown at 85 in Figure 9, then the strip 48 extends past the grooves and ridges 83 and 84, and a crease or indentation 75 is formed in the strip 48 along the fold lines 86.

It is also to be noted that the pressure exerted by the top roll 43 is adjustable by means of springs 87 and adjusting nuts 88, since the shaft 41 for the top roll is freely retained in slots 89, the bottoms of which form the bearings for shaft 41 and which shaft is pressed into the slots 89 by spring pressure. The pressure exerted by feed roll 43 is preferably sufficient to tightly grip the strip 48 to prevent any slippage thereof, thus insuring that the length of each card or boat is uniform, and each boat is properly indented along the fold line.

The discharge feed rolls 69 and 70 are of substantially the same size and the lower roll 70 is substantially smooth. The upper roll 69, however, is provided with a central flat portion 91 and adjacent recessed portions 92 circumferentially thereof. When cards are being formed, the central flat portion 91 grips the strip between itself and bottom roll 70, and feeds the cards to the pockets, as best shown in Figures 16 and 17. When boats 85 are being formed, however, they are folded in a manner hereinafter described so that the edges of the strip 48 are doubled over, as shown in Figure 8, and the doubled portion is received in the recessed portions 92 of the top discharge feed roll 69.

The top discharge feed roll 69 is also freely retained in a slot 90 in the bearing member 64 and springs 93 exert pressure on the feed roll 69, which pressure is adjustable by means of nuts 94. The gearing for the feed rolls 69 and 70 is arranged so that these rolls tend to deliver the strip 48 to the pockets 35 a trifle faster than the feed rolls 43 and 44 supply it, and the springs 93 are so adjusted to permit slight slippage of the feed rolls 69 and 70 relative to the strip 48, thus insuring that the cardboard strip between the feed rolls 43, 44 and 69, 70 is taut at all times. This is particularly important for forming boat 85, as will be apparent hereinafter.

A cutting knife 95a is pivotally mounted at 96a on one of the bearing members 64, and is yieldably held against the front face of the bearing blocks 64 by a bolt 97 and is biased by a spring 98. The knife 95 is positioned close to the strip outlet from the discharge feed rolls 69 and 70, as is apparent in Figures 11 and 15, for example.

The cutting knife 95a is periodically lowered and raised by a lever 101 pivotally supported on mounting bar 34, as shown at 102. An upright member 103 has its lower end pivotally secured at 104 to an intermediate portion of lever 101 and its upper end pivotally secured at 105 at an angle of 90° from the pivot 104. The end of lever 101 opposite pivot 102 is provided with a roller 106 which rides on cam 63. As cam 63 moves to lower positions, the lever 101 and knife 95a are lowered by gravity to effect cutting of strip 48 as it is discharged from rolls 69 and 70. The cutting knife is at its lowermost position to cut strip 48 when the flat portions 81 and 82 of gears 32 and 78 are in engagement and the feed rolls, therefore, are at rest, as will be apparent from the position of these parts as shown in Figures 1, 10 and 11.

Referring now to Figures 13, 14 and 15, for example, for a detailed description of the boat former attachment, as stated before, it comprises primarily two guide fingers 54 and 55, which are provided with outwardly extending lugs 107 having adjusting slots 108 therein. Bolts 109 extend through the slots 108 and are screwed into the

bed-plate 51. The slots 108 provide adjustment for different width strips 48.

The guide fingers 54 and 55 are identical in shape and are formed with an outwardly flared surface 111 which curves over into an inwardly flared surface 112. As best shown in Figures 7 and 8, the indented strip 48 feeds into the outwardly flared portion 111 and is progressively bent or folded along the indentations until the material is doubled over, as shown at 113 in Figure 8. When the doubled strip is fed into a pocket 35 and cut off, the bent marginal portions spring upright due to the inherent flexibility of the cardboard material and assume the boat shape shown in Figure 9.

A strip hold-down plate 114 is positioned above the strip 48 as it passes between the boat formers 54 and 55 and is adjustably held in position as to height by two brackets 115 having two studs 20 and bars 116 secured thereto and to the hold-down plate 114. Vertical slots 117 in brackets 115, into which bars 116 extend, provide for the aforesaid adjustment.

When it is desired to form cards instead of boats, the boat formers 54 and 55 and hold-down plate 114 are removed, and a card guide 118, shown in Figures 16 to 18 inclusive, is attached. The card former merely comprises a substantially flat sheet of metal which is screwed to bed plate 51 by screws 119 and is provided with a trough 121 which converges into a guiding portion 122, the sides of which are parallel. The strip 48 passes through the guiding portion 122 just before it reaches discharge feed rolls 69 and 70, thus insuring that the strip 48 will be centered and will be cut off at right angles.

Operation of Figures 1 to 15

Referring now to Figures 1 to 15 inclusive for a description of the operation of the mechanism when boats are to be formed, the reel 49 of cardboard strip material 48 is set up on a suitable spindle and the strip material is manually threaded under guide roll 47, then into feed rolls 43 and 44. The pressure on the feed rolls 43, 44 and 69, 70 is adjusted and the machine is started by energizing the motor 21. The motor drives the various gears, pinions, sprockets and chains and power is transmitted through chain 28 and sprocket 29 to the main driving gear 32. Gear 32 is thereby rotated and rotates driven gear 78 as long as the teeth of the two gears are in mesh, and does not drive gear 78 when the flat portions 81 and 82 are in engagement, thereby stopping the feed rolls 43, 44 and 69, 70, and preventing the strip 48 from moving at this time. The cam 63 is rotated continuously by the shaft 31 on which main gear 32 is mounted and knife 95a is moved up and down. The knife 95a is in the cutting or down position at the time feed rolls 43, 44 and 69, 70 are stopped, thereby delivering a boat 85 to each pocket 35. The conveyor chain 36 is also stopped at the time the feed rolls are and when the knife cuts off a boat, it is delivered into pocket 35.

The actual forming of the boat 85 by boat formers 54 and 55 has already been described and need not be repeated again.

After the boat is in the pocket 35, the article to be wrapped is placed therein and is wrapped by suitable mechanism. Since the article feed and the wrapping form no part of the present invention, description thereof is unnecessary.

Operation of Figures 16 to 18.

The operation of the mechanism shown in Figures 16 to 18 inclusive, is exactly the same as described with respect to Figures 1 to 15, except that the card guide 118 is utilized and knife 95a cuts off flat cards instead of boats and delivers them to the pockets 35.

Some changes may be made in the construction and arrangement of the parts of my packaging machine for candy, cakes and the like without departing from the real spirit and purpose of my invention, and it is my intention to cover by my claim any modified forms of structure or use of mechanical equivalents which may be reasonably included within their scope without sacrificing any of the advantages thereof.

I claim as my invention:

In a packaging machine, the combination of a moving conveyor having a plurality of open-ended U-shaped article receiving pockets, a source of supply of continuous relatively rigid strip material and a feed mechanism for feeding said strip material from said source of supply to said pockets in the form of predetermined folded lengths, said feed mechanism comprising a set of feed rolls receiving said strip material from said source and provided with means for creasing said strip material longitudinally to define folding lines in said strip material, means for bending the marginal edges of said strip material over upon themselves along said folding lines, discharge rolls receiving said folded

strip material, one of said discharge rolls being formed with spaced peripheral grooves capable of receiving said folds freely so that traction on said folded strip material by said grooved discharge roll is exerted only by the roll area between said grooves, means for rotating said discharge rolls faster than said feed rolls, cutting means for said strip material adjacent said discharge rolls, and automatic means for operating said cutting means to cut said folded strip material into predetermined lengths as the strip material emerges from said discharge rolls, said discharge rolls being operative to deliver said folded cut strip material to said receiving pockets.

OSCAR SANDBERG.
